United States Patent Office

Des. 196,522
Patented Oct. 8, 1963

196,522

VELOCIPEDE

Viktor Schreckengost, Cleveland Heights, Ohio, assignor
to The Murray Ohio Manufacturing Co., Nashville,
Tenn., a corporation of Ohio

Filed Nov. 20, 1962, Ser. No. 72,555

Term of patent 14 years

(Cl. D34—15)

Fig. 1.

Fig. 2.

*Fig. 3.**Fig. 4.*FIGURE 1 is a front perspective view of a velocipede, showing my new design;

FIGURE 2 is a rear elevational view thereof with the broken line showing of the seat portion omitted for convenience of illustration;

FIGURE 3 is a side elevational view thereof; and

FIGURE 4 is a top plan view thereof with the broken line showings of the seat portion and the handle-bar omitted for convenience of illustration.

The dominant features of my design reside in the portions shown in full lines.

I claim:

The ornamental design for a velocipede, substantially as shown and described.
